METHOD AND MEANS FOR LOOPING
HOSIERY

John A. Pons, Morganton, N. C.

Application July 2, 1937, Serial No. 151,719

4 Claims. (Cl. 112—25)

This invention relates to the manufacture of hosiery and the like, and more especially to a method and means of performing a looping operation upon the foot portion thereof. It is a well known fact, in the manufacture of hosiery, that full-fashioned hose are knitted in a flat position, and when the top, leg and foot portions are assembled it is necessary to perform certain looping and seaming operations in order that the developed, flat, knitted portion will assume the shape of a hose to conform to the leg of the wearer. In certain portions of the foot of the hose, it is necessary to loop a selvedge and a ravel edge together, it being understood that the ravel edge of a knitted fabric is always disposed substantially at right angles to the selvedge where the dissection of the courses of yarn is reversed. In order to do this, both of said edges must be placed upon the same needles loop for loop, and then the excess portions of the ravel edge are removed so that when the looping machine, during the looping operation, inserts a thread to join the loops together there will not be a large rib at the junction point. Therefore, it is very desirable that the ravel edge be clipped off as closely as possible to expedite the removal of the excess fabric. Then a suitable brushing mechanism should be employed to further ravel this edge down to the needles or points so that only the bare loops of the respective edges will be disposed upon the needles during the looping operation.

Heretofore, it has been very difficult to unravel the ravel edge because a shearing operation could not be employed for fear that the selvedge would be cut, thereby causing a run in the hose; consequently, this ravelling has to be performed by hand. I have provided an improved guard whereby the selvedge will be protected while the ravel edge will be exposed to a suitable shearing apparatus which will clip this edge down very closely along a line slightly above the needles without in any manner, exposing or cutting the selvedge.

It is therefore, an object of this invention to provide in a looping machine having needles, means for securing a ravel edge and a selvedge loop for loop on the same needles, and means for guarding the selvedge while the ravel edge is being sheared down to substantially the same elevation as the selvedge.

It is a further object of this invention to provide an apparatus of the class described with further means for brushing the ravel edge after it has been sheared to loosen the excess yarn

above the needles. Also means are provided for clipping and removing any of the loose threads which may be disposed above the course which is held by the needles, after which further means are employed for looping the selvedge to the ravelled edge loop for loop, to unite the edges. By properly guiding the selvedge while the ravel edge is being sheared to substantially the same point as the selvedge, it is possible to employ the brushing and clipping operation so as to remove the surplus thread which may be disposed above the course held by the needles; whereas, if the clipping operation were not possible the ravelled edge would have to be unravelled by hand down to the desired point which would entail much time and expense in the production of hosiery.

Some of the objects of the invention having been stated, other objects will appear as the re-description proceeds, when taken in connection with the accompanying drawings, in which:

Figure 1 is a plan view of a portion of a dial looper showing my invention applied thereto;

Figure 2 is a sectional view taken along the line 2—2 in Figure 1 showing the thread clipper and remover;

Figure 3 is an elevation of Figure 1, but omitting certain parts of the looping mechanism;

Figure 4 is a detail of the upper left-hand portion of Figure 3 but showing the omitted looping mechanism and its associated parts;

Figure 5 is an enlarged, sectional view taken along the line 5—5 in Figure 1 showing the opposite side of the thread clipper and remover from that shown in Figure 2;

Figure 6 is an enlarged, sectional view taken along line 6—6 in Figure 1;

Figure 7 is an enlarged, sectional view taken along the line 7—7 in Figure 1;

Figure 8 is an enlarged, sectional view taken along the line 8—8 in Figure 1;

Figure 9 is an enlarged, isometric view of a portion of a dial looper showing the manner in which my improved guard protects the selvedge while the ravel edge is being sheared down to substantially the same elevation;

Figure 10 is an inverted isometric view of one end of the guard shown in Figure 9;

Figure 11 is a plan view of a developed foot portion of a full-fashioned hose prior to its edges being looped together.

Figure 12 is an enlarged elevation of a portion of knitted fabric showing the manner in which the selvedge is placed upon the points.

Referring more particularly to the drawings, the numeral 10 denotes a suitable bench or sup-

port to which is secured an overhanging cantilevered frame 11 which supports a dial race 12, said race depending from the extreme outer end of frame 11. This dial race has a dial ring 13 secured thereon by means of screws 14, the function of this clamp being to hold a dial ring 15 in its proper position. The dial ring 15 supports a point or needle ring 16 upon which a plurality of needles or points 17 are adapted to 5 rest with their sharpened ends projecting beyond the periphery of point ring 16 so that the loops of a fabric such as a hose may be placed thereon. A plurality of point clamps 18 are 10 adapted to rest upon the shanks of points 17 15 to hold them in fixed position against the point ring 16. These point clamps 18 are held in position against the point and dial ring respectively, by any suitable means such as screws 19. The dial ring 15 has integral therewith a suitable 20 rack 15a which is engaged by conventional gears, not shown, to cause the dial ring to rotate slowly about the dial race 12. This rack is protected by a suitable rack guard 22 which, in turn, is secured to the bottom portion of dial race 12, see 25 Figure 4.

Secured to the dial race 12 as at 23 is a holding arm 24 which bows around the edge or periphery of the dial ring and supports a fabric guard plate 25 in the position shown in Figures 30 1, 5, 7, and 8. Secured to the guard plate 25 by any suitable means such as screws 26, is a thin L-shaped plate 27 which acts as a point guard beneath which points 17 are adapted to pass as they carry the fabric through the machine. This 35 plate has a point 27a, the end of which is disposed immediately above the ends of the moving points of needles 17. The plate 27 has integral therewith an upstanding leg 28 which cooperates with the edge 29 of this plate (Fig. 1) 40 to cause the fabric to be pushed to the proper position upon the needles so that it may be sheared in the next operation.

Figure 11 shows full-fashioned hose before the parts are looped together. This hose is designated by the reference character 35. In order to properly loop the parts together the respective edges must be joined loop for loop and a thread inserted into these loops. It is seen that the hose 35 has flaps or side portions 36, each of which 45 have a selvedge 37. It is further seen that this hose has another flap or portion 38 and these portions have a ravel edge 39. It is necessary to join the edge 37 to the portion 38 along dotted line 40 in order to properly form a finished stocking. As heretofore stated, it has been customary 50 to place the portion 38 upon the points 17 along dotted line 40, this course being a few courses down from the extreme upper edge 39. Then the edge 37 of the selvedge 36 was placed upon the needles or points, after which, the course above 55 the dotted line 40, were unravelled by hand. It was absolutely necessary that this ravelling take place by hand since if any of the loops of the selvedge 37 were to be severed a run would be 60 caused in the stocking thereby forming a defective stocking. This method of removing the surplus yarn is slow, tedious, and expensive.

In practicing my invention, portions 36 and 38 are placed side by side and the portion 38 is 65 first placed upon the points 17 with the points penetrating the same along dotted line 40, thereby leaving a portion 39 disposed above the needles as shown in Figures 6, 7, 8 and 9. Then the edge of selvedge 37 is placed on the points 70 17. As the dial ring rotates in a clockwise man-

ner in Figure 1, the stocking is carried along with the points, and when the guide point 27a is contacted, the portion 39 which is disposed above the needles 17 will be pushed inwardly to the proper position where it will be guided by the 5 surface 29 and the upstanding leg 28 of plate 27.

In order to insure that the selvedge 37 will not be disturbed, while the portion 39 is being severed a suitable guard plate 42 has been secured to the top of plate 27 by means of the screw 26. 10 This guard has a slot 42a therein so that the proper adjustment may be effected. The other end of the guard plate 42 projects to the left in Figures 1 and 9, and its end is disposed over the needles or points 17. This guard has a down-turned portion 43 normally resting upon needles 17, which portion forms a slight recess or groove 44 along the lower edge thereof, so that the selvedge 37 may pass therebeneath, Figures 8 and 10. At the same time, the ravel edge 39 slides 20 against the down-turned edge 43 so that its portions will be exposed to reciprocatory knife 45. This knife is mounted in bell crank 46 which oscillates about point 47 to cause said knife to move back and forth relative to stationary knife 25 48 which in turn, is secured to a block 49 by means of screw 50.

Also secured in the lower end of bell crank 46 is a packer 54 which has a packing edge 55 for contacting the portion 39 and moving it toward 30 the center of rotation of the dial ring. This will prevent any portions of this edge 39 from moving into the groove 44 beneath the guard 42, but instead the edge will move beyond this groove and be exposed to the cutting edges of knives 45 and 48 as the points pass thereby. Figures 8 and 9 show the manner in which the selvedge 37 passes into the recess 44 and is thereby protected from the cutting edge, since the knife 45 is adapted to reciprocate directly above guard plate 42. 40

The bell crank 46 has pivotally secured to its other end a link 56 which link is operated by means of a disk or wheel 57, said disk 57 being fixedly secured around rotating shaft 58. It is seen by referring to Figures 1 and 3 that as the 45 shaft 58 rotates, oscillatory motion is imparted to the crank 46 to thereby cause the blade 45 to oscillate and shear the portion 39 down to substantially the same elevation as the selvedge 37, Figure 9. 50

When this shearing operation has been effected it is necessary that the remaining severed edges of the course above the course held by the needles 17 be removed so that when the looping operation takes place to join the portions together, 55 loop for loop, a perfect union will be effected thereby preventing a large rib or seam at the junction point. In order to remove or loosen these remaining threads from the course held by the needles 17, a suitable oscillating brush 60 has 60 been provided with the lower edge thereof disposed directly against the top of the points 17 so that the ravel edge will be loosened. Means have also been provided for oscillating this brush as the points 17 pass beneath it along with 65 the edges of the stockings which are to be united. This brush is fixedly secured around shaft 61 which shaft is rotatably mounted in bracket 62. The bracket 62 is secured to trimmer frame 63 which, in turn, is secured to the dial race 12. 70 This trimmer frame also supports bracket 65 to which bell crank 46 is pivotally secured.

The shaft 61 has fixedly secured on the other end thereof an upwardly projecting lever 66, and pivotally secured to this lever is one end of link 75

67. The other end of link 67 is pivoted to the end of lever 68, said lever being fixedly mounted on rotating shaft 69. As the shaft 69 rotates it is seen that the lever 66 will be oscillated back and forth in Figure 3 to thereby cause the lower portion of the brush 60 which contacts the edges of the stocking held by points 17, to loosen and unravel the excess thread in the portion 39.

After the brush 60 has performed the function of loosening and partially removing this excess yarn from the portions 39, it is necessary to employ other means for entirely removing these loosened ends so that they will not be looped at the junction point during the subsequent looping operation. I have therefore, provided a plate 75 which has a plurality of spaced racks 76 projecting upwardly and outwardly therefrom (Figures 1, 3 and 5). This plate is secured to the top of plate 25 by means of screw 77 and is positioned in the manner shown in Figures 1 and 5 so that the sharpened ends of points 17 will pass directly beneath one edge of plate 75. This of course, will cause the upper ravel course of portion 38 as well as the selvedge 37 to pass along the right hand edge of plate 75 as shown in Figure 5 so that any excess loose yarn or thread will be exposed to downwardly projecting prongs 80. The upper ends of these prongs are secured to a suitable bar 81 which, in turn, is supported by bolt 82. The bolt 82 is mounted for oscillation in bracket 83, and this bracket is secured to another bracket 84 by any suitable means such as screws 85. The bracket 84 has the lower end thereof secured to dial ring clamp 13 (Figures 2 and 5).

Since the bolt 82 has knife 86 (Figure 2) fixedly secured to one end thereof, it is evident that as the knife 86 is oscillated, the points 89 will likewise be oscillated so that the lower ends thereof will engage any loose ends of the yarn or thread and move them upwardly and outwardly upon the toothed racks 76.

When the loose ends are once moved upon these toothed racks by the prongs 80, the teeth in the racks will prevent the ends from again moving downwardly upon the top of the edges which are to be united.

It is also necessary that these loose ends be severed so that unusually long pieces will not be moved upon rack 76. In order to provide this severing means a stationary blade 88 has been adjustably secured to the side of bracket 84 by means of screws 89.

Knife 86 has a cutting edge 90 which is adapted to cooperate with cutting edge 91 on the lower end of blade 88. A U-shaped member 92 is also loosely mounted around the bolt 82 and encircles the back of knife 86 and has portions disposed on each side of knife 86 (Figures 2 and 5). This member 92 has points 94 and 95 on its lowermost portion which are adapted to gather up the loose ends and cause them to be moved upwardly into engagement with the cutting edges of the knives.

It is seen that this member 92 is normally held against the back of knife 86 by any suitable means such as tension spring 97, and although the member 92 is moved in a counter-clockwise manner, in Figure 2, by virtue of the movement of the rotation of blade 86, the clockwise rotation of member 92 is nevertheless effected by the tension spring 97. Therefore, it is seen that there is no positively actuated means for causing clockwise movement of member 92. This is important since, if this member should become clogged, then

the positive clockwise movement of the knife 86 will not actuate the member 92.

The knife 86 has secured in the upper end thereof a suitable pin 99 in which one end of link 100 is mounted. The other end of link 100 has its end mounted in arm 101 which, in turn, is secured to link 56. Each time a revolution of shaft 58 is made, the knife 86 as well as the member 92, is caused to oscillate, thereby cutting any of the loose edges to allow the prongs 80 to move them upon the rack teeth of members 76.

After these loose ends have been removed the points 17 only hold the uppermost loops of the respective edges, therefore, it is only necessary to employ the conventional looping mechanism to insert a thread and unite these courses loop for loop. This is effected by a suitable needle 103 (Figure 4) which is adjustably mounted in the lower end of arm 104, said arm being pivotally secured as at 105 to the needle arm sliding shoe 106. This arm is secured on the right-hand end of slotted needle arm cam lever 107 which is held in position relative to bracket 108 by any suitable means such as pin 109, said pin penetrating slot 110 in this lever. The other end of lever 107 has a suitable roller 112 which is adapted to fit in peripheral groove 113 of cam 114, said cam 114 being fixedly mounted on shaft 58. The shaft 58 also has fixedly secured thereon an eccentric 115 around which is mounted one end of link 116. This link is pivoted as at 117 to a second link 118 which has its other end pivotally secured as at 119 to an intermediate portion of lever 104. As the shaft 58 rotates, it is seen that the eccentric 115 will cause the lever 104 and its associated needle 103 to oscillate back and forth about point 115, in Figure 4, to thereby loop the heel gussets 36 and 38 together along the edges 37 and 40 respectively. The cam 114, lever 107 and its associated parts are provided to impart the same rate of travel to the needle 103 as the rate of travel of the points 17 as they pass by the needle at this point thereby insuring that each of the loops will be accurately centered by the point 45 of the needle 103.

When a hose is first placed upon the points as shown in Figure 3, it is very essential that downward tension be applied to the portions 36 and 38 so that the top loops held by the needles or points 17 will not be severed by the shearing knife 45. I have therefore, extended a member 118 downwardly from the dial race 12 and around the lower end of this member I have rotatably mounted a suitable collar 119. This collar carries a ring 120. Upon this ring, a plurality of straps 121 are secured, which are preferably made of elastic material. The upper ends of these straps have hooks 122 which are used to penetrate the portions 36 and 38 when they have been properly positioned upon the points 17. It is seen that in this manner, the courses in the respective portions which are desired to be united will be pulled tautly downwardly on the needles so that it will be impossible for any of these courses to be severed by the shear knife but only will allow the projecting portions 39 to be contacted.

Theoretically, the points 17 should penetrate the extreme outer loop of the selvedge in order that the rib at the junction point might be of 70 minimum size. From a practical standpoint, this is impossible; consequently, the points must penetrate the selvedge one or two wales from the extreme outer loops so that the operators will have a very narrow projecting edge which may

be grasped by their fingers while placing the edge upon the points.

Figure 12 is a very much enlarged view showing the selvedge and the location of the points 5 17 when penetrating the same. In the other views, the projecting edge of the selvedge above the needles has been omitted for the sake of clearness, however, the thickness of this projecting portion is not sufficient to provide a noticeable 10 rib when looped to the ravel edge.

In the drawings and specification there has been set forth a preferred embodiment of the invention, and although specific terms are employed, they are used in a generic and descriptive 15 sense only, and not for purposes of limitation, the scope of the invention being set forth in the appended claims.

I claim:

1. In a dial looper for uniting the selvedge edge 20 of the heel portion and the ravel edge of the foot portion of a full-fashioned stocking having means for imparting rotation thereto, said looper having a plurality of points for penetrating the selvedge edge at its extreme edge and for penetrating the 25 ravel edge at a point removed from its extreme edge, a stationary guard disposed immediately outside the path defined by the points in their rotation and beneath which the selvedge edge is adapted to pass, a reciprocable knife 30 having means for reciprocating the same across the upper side of said guard and across and above said points to sever the ravel edge down to the loops disposed on said points, and means for looping the two edges together.
2. In a dial looper for uniting the selvedge edge of the heel portion and the ravel edge of the foot portion of a full-fashioned stocking having means for imparting rotation thereto, said looper having a plurality of points for penetrating the 35 selvedge edge at its extreme edge and for penetrating the ravel edge at a point removed from its extreme edge, a stationary guard disposed

immediately outside the path defined by the points in their rotation and beneath which the selvedge edge is adapted to pass, a reciprocable knife having means for reciprocating the same 5 across the upper side of said guard and across and above said points to sever the ravel edge down to the loops disposed on said points, means for brushing the severed portions from the ravel edge, and means for looping the two edges together. 10

3. That method of uniting the selvedge edge of a heel portion and the ravel edge of the foot portion of a full-fashioned stocking which comprises supporting the ravel edge a short distance from its edge, and supporting the selvedge edge 15 at its extreme edge, applying tension to the stocking to hold the loops tautly at their points of support, then packing the loops of the ravel edge on the support for same, then guarding the selvedge edge, then severing the portion of the 20 ravel edge immediately above its point of support, and then passing a looping thread between the loops of the two edges to unite the two edges together.

4. That method of uniting the selvedge edge of a heel portion and the ravel edge of the foot portion of a full-fashioned stocking which comprises supporting a course removed from the ravel edge, also supporting the outermost loops of the selvedge edge, applying tension to the stocking to 30 hold the loops tautly at their point of support, then packing the supported loops of the ravel edge, then guarding the selvedge edge, severing the portion of the ravel edge immediately above their point of support, then brushing the severed 35 portions from the stocking, then forcing undesirable portions of the threads away from the ravel edge, then passing a looping thread between the loops of the two edges to unite the two edges together. 40

JOHN A. PONS.
